UNITED STATES PATENT OFFICE.

HANS OLOF LINDGREN, OF STOCKHOLM, SWEDEN, ASSIGNOR TO THE DE LAVAL SEPARATOR COMPANY, OF NEW YORK, N. Y., A CORPORATION OF NEW JERSEY.

MEANS FOR CONSERVING CENTRIFUGED LIQUIDS.

Application filed July 27, 1926, Serial No. 125,315, and in Sweden July 29, 1925.

In the operation of centrifugal separators and purifiers the liquid or liquids are usually discharged from the centrifuge into a surrounding collecting vessel or vessels in a finely divided state. The rapidly rotating separator bowl causes strong air currents in the collecting vessels. If these vessels are in open or restricted connection with the atmosphere, more or less air will flow into and out of the collecting vessels, and the air escaping from the collecting vessels into the atmosphere will carry with it more or less of the finely divided liquid. If the liquid discharged from the separator is so volatile as to be partly or wholly converted into a vapor, the air will carry more or less of this vapor into the atmosphere. If the finely divided liquid or vapor is oxidizable, it may combine with the oxygen of the air, and not only will some of the reaction product escape into the atmosphere, but there may be some danger of an explosion. For example, in the purification and separation of crude oil containing gasoline, the gasoline may in part evaporate, and the air currents will not only carry off evaporated gasoline, but will entrain with it finely divided particles of the liquid gasoline and if the air be present in sufficiently large proportion it may combine with gasoline to form an explosive mixture. Thus there results a substantial loss of gasoline and the formation of objectionable reaction products, with danger, in some cases, of explosion.

It is theoretically possible to prevent loss of finely divided liquid and vapor by preventing the admission of air to, and the discharge of air from, the collecting vessels. It is difficult, however, to maintain the collecting vessels air-tight with respect to each other and to maintain the lower collecting vessel air-tight with respect to the frame in which the separator is erected, although means for so doing have been proposed. The difficulty in providing the necessary air-tight conditions arises from the fact that the rotating separating bowl produces a superatmospheric pressure in some of these chambers, so that gases escape through fissures through which there would be a negligible gas flow if the pressure in the chambers were that of the atmosphere.

The object of the present invention is to effectively prevent the escape of gas and liquid from the collecting vessels, or either of them, even in the absence of absolutely air-tight closures between the collecting vessels and

between these vessels and the frame. Devices embodying my invention in preferred forms and adapted to accomplish said object are shown in the accompanying drawings, in which—

Fig. 1 is a side elevation of an apparatus embodying my invention.

Fig. 2 is a partial view of a modification.

Within the sustaining and enclosing frame 1 of the centrifugal machine is mounted a rotatable centrifugal bowl 2, and supported on the frame are collecting vessels 3 and 4 in communication, respectively, with the heavier liquid discharge, and the lighter liquid discharge, of the separator bowl. Precautions should be taken to prevent unrestricted communication between the collecting vessels, and between each collecting vessel and the surrounding or adjacent spaces, but air-tight constructions are unnecessary due to the maintenance, by means to be described, within the collecting vessels, of a partial vacuum which will exclude outflow of air or gas therefrom. From the collecting vessels 3 and 4 extend the respective pipes 5 and 6 to the respective receiving tanks 7 and 8. Into the latter flow the separated liquids together with any part of the separated fluid that has vaporized, any air that has been sucked into the collecting vessels, and any finely divided liquid that is entrained in the air and vapor. The gas space in the tanks 7 and 8 communicate with a pipe 9 leading to an injector 10. The injecting nozzle of the injector is connected, through a pipe 11 (in which is interposed a pump 12), with a tank 13, which contains a suitable liquid that is not miscible with the centrifuged substance that has been discharged into the tanks 7 and 8. Beyond the injector 10 is a gravity separator 14 communicating, through a pipe 15, with the tank 13. Beyond the separator 14 is a pipe 16, which may lead to a suitable discharge, directly or through a condenser 17.

In operating the described apparatus, the injector may first be operated to create the desired degree of vacuum in the collecting vessels 3 and 4 and in the entire system between these vessels and the injector. After the centrifuge is started, the finely divided particles of liquid that escape from the collecting vessels and do not settle in the tanks 7 and 8, and any evaporated fluid, as well as any air that has been sucked into the collecting vessels, all come in contact, at the injector 10, with the

liquid drawn from the tank 13. The finely divided centrifuged liquid is absorbed in the injected liquid and these liquids will drop, through pipe 15 into tank 13. The air is removed through pipe 16, and, if it contains any condensable vapor, should be passed through a condenser 17, in which the vapor is condensed and separated. The condenser may, of course, be located at some other point in the system, 10 as, for example, back of the injector 10, as shown at 18 in Fig. 2, so that the injecting liquid will operate only on air and finely divided liquids.

In Fig. 1, both collecting vessels 3 and 4 are 15 shown connected with tanks (7 and 8) closed to the atmosphere, so that no air can enter the liquid discharge system except such small amount as may directly be sucked into the collecting vessels. In the separation of crude 20 oil containing great quantities of liquid emulsion, it is not suitable to connect the lower collecting vessel 3 with a closed tank; but a construction embodying my invention may be used to advantage by giving the pump a 25 greater capacity.

The particular fluid that may be used to best advantage as the injecting fluid will depend on the character of the liquids that are separated in the centrifuge. In many instances, the purified liquid discharged into the 30 collecting vessel 4 may be used as the injecting fluid, in many cases, water may be injected.

Where the character of the purified or separated liquids that are discharged from centrifugal purifiers or separators in finely divided form is such that they tend to react chemically with air to form an objectionable mixture, as, for example, any oxidizable liquid, it is known to prevent the formation of objectionable mixtures or compounds by displacing the air in the space adjacent the discharge, that is, in the collecting vessels, or in both the collecting vessels and the centrifuge, with a 40 neutral gas that does not tend to react chemically with such liquid. In such case, the pressure within the liquid discharge system will be preferably, although not necessarily, more or less above atmospheric so as to more effectively insure against admission of air to the 45 collecting vessels. In any case, the gas discharged through the pipe 16 should be so re-conducted to some point in the system as to maintain the desired atmosphere of neutral gas in the collecting vessels. For example, the pipe 16 may be connected with one or 50 both of the collecting vessels 3 and 4 so as to establish an endless circulation of neutral gas. This is indicated at the left in Fig. 1, where the pipe 20 in dotted lines represents 55 the described extension of pipe 16.

Other examples of uses to which my improvement is adapted are as follows: When separating f. i. fuel oil, it may be suitable to use an injection liquid f. i. already separated 60 fuel oil. When separating a lubricating oil

in a closed system, it may be suitable to use a lubricating oil injection liquid.

Having now fully described my invention, what I claim and desire to protect by Letters Patent is:

1. The combination with a centrifuge of the type wherein a substance subjected to the action of centrifugal force is discharged in finely divided form, of a collecting vessel into which said centrifuged substance is adapted to 70 be discharged, and means adapted to establish a partial vacuum in said collecting vessel and to separate the finely divided liquid from any gas in which it is entrained. 75

2. The combination with a centrifuge of the type wherein a substance subjected to the action of centrifugal force is discharged and when so discharged is partly in a finely divided liquid state and partly in the form of vapor, and an apparatus adapted to prevent loss of 80 the centrifuged substance; said apparatus comprising means to establish a partial vacuum in the discharge from the centrifuge and to separate the finely divided liquid from gas and means to condense said vapor. 90

3. The combination with a centrifuge of the type wherein a substance subjected to the action of centrifugal force is discharged in finely divided form, of a collecting vessel into which said centrifuged substance is adapted to 95 be discharged, and means to establish a flowing stream of such centrifuged substance from 100 said collecting vessel and prevent loss thereof and separate therefrom any air admixed therewith; said means comprising an injector adapted to forcibly inject a liquid into the flowing stream, thereby creating a partial vacuum along the course of said stream and in 105 said collecting vessel, preventing escape of air from said collecting vessel except along the course of said stream, and absorbing the finely divided centrifuged substance in the injecting liquid. 110

4. The combination with a centrifuge of the type wherein a substance subjected to the action of centrifugal force is discharged in finely divided form, of a collecting vessel into which said centrifuged substance is adapted to be discharged, and means to establish a flowing stream of such centrifuged substance and 115 separate therefrom any air admixed therewith; said means comprising an injector adapted to inject a liquid into the flowing stream and thereby absorb such part of said substance as may be in a finely divided liquid 120 state and a condenser adapted to condense such part of said substance as may be in the form of vapor. 125

5. The combination with a centrifuge of the type wherein a substance subjected to the action of centrifugal force is discharged in finely divided form, of a collecting vessel into which such centrifuged substance is adapted to be discharged, a receiving tank connected with the collecting vessel, means to al- 130

low the escape of gas from the tank, and an injector adapted to inject liquid into the out-flowing gas and thereby absorb any liquid in finely divided form that escapes from the tank 5 with said gas and effect the separation from such liquid of such gas.

6. The combination with a centrifuge of the type wherein a substance subjected to the action of centrifugal force is discharged 10 in finely divided form, of a collecting vessel into which such centrifuged substance is adapted to be discharged, a receiving tank connected with the collecting vessel, and means to establish a flowing stream of gases 15 from the tank and separate therefrom condensable vapor and entrained centrifuged liquid; said means comprising an injector adapted to inject liquid into the flowing stream and a condenser: whereby the centrifuged liquid is absorbed in the injected liquid and the condensable vapor is condensed and both separated from any non-condensable gas that leaks into and outflows 20 from the collecting vessel.

25 7. The combination with a centrifuge of the type wherein a substance subjected to the action of centrifugal force is discharged in finely divided form, of a collecting vessel into which such centrifuged substance is 30 adapted to be discharged, a receiving tank connected with the collecting vessel, a gas outflow conduit from the tank, an injector adapted to inject liquid into said conduit and thereby absorb any liquid in finely divided 35 form that may be entrained in the gas out-flowing through said conduit, and a pipe connected with said conduit and adapted to convey the separated gas to the collecting vessel wherein it is again mixed with the discharging 40 centrifuged substance.

8. In centrifugal purification or separating operations wherein a liquid subjected to the action of centrifugal force is discharged in a finely divided form, the process of preventing loss of said finely divided liquid which 45 comprises providing an outflow from the locus of centrifugation for gas in which said finely divided liquid is entrained and forcibly injecting a liquid into the flowing stream 50 of gas thereby maintaining the discharge from the centrifuge under partial vacuum and absorbing the entrained liquid before allowing the gas to escape.

55 9. In centrifugal purification or separating operations wherein a liquid subjected to the action of centrifugal force is discharged in a finely divided form, the process of preventing loss of the centrifuged substance which comprises outflowing from the locus 60 of centrifugation any foreign gas carrying finely divided centrifuged substance, contacting the said outflowing gas and liquid with another liquid and separating the gas from the centrifuged substance by absorbing the 65 centrifuged substance in such other liquid.

10. In centrifugal purification or separating operations wherein a liquid subjected to the action of centrifugal force is discharged in finely divided form in admixture with gas and vaporized centrifuged substance, which 70 comprises outflowing from the locus of centrifugation the said gas together with any finely divided liquid and vapor carried thereby and separating the centrifuged substance from the gas, said separating operation comprising the condensation of the vapor and the absorption of the finely divided centrifuged liquid in another liquid.

11. In centrifugal purification or separating operations wherein a liquid subjected to the action of centrifugal force is discharged in a finely divided form, the process of preventing loss of the centrifuged substance which comprises outflowing from the locus of centrifugation any foreign gas carrying 85 finely divided centrifuged substance and maintaining a partial vacuum on the centrifuged substance while at the same time effecting a separation of the centrifuged substance from the gas carried thereby.

90 12. In centrifugal purification or separating operations wherein a liquid subjected to the action of centrifugal force is discharged in finely divided form in admixture with gas and vaporized centrifuged substance, which 95 comprises outflowing from the locus of centrifugation the said gas together with any finely divided liquid and vapor carried thereby and maintaining a partial vacuum on the 100 centrifuged substance while at the same time separating both the finely divided liquid and the vapor from the gas.

13. In centrifugal purification or separating operations wherein a liquid subjected to the action of centrifugal force is discharged 105 in a finely divided form, the process of preventing loss of the centrifuged substance which comprises outflowing from the locus of centrifugation any foreign gas carrying finely divided centrifuged substance and 110 maintaining a partial vacuum on the centrifuged substance while at the same time separating the gas from the centrifuged liquid carried thereby by absorbing the finely divided liquid in another liquid.

115 14. In centrifugal purification or separating operations wherein a liquid subjected to the action of centrifugal force is discharged in a finely divided form in admixture with gas and vaporized centrifuged substance, 120 which comprises outflowing from the locus of centrifugation the said gas together with any finely divided liquid and vapor carried thereby and maintaining a partial vacuum on the 125 centrifuged substance while at the same time separating the centrifuged substance from the gas by condensing the vapor and absorbing the finely divided centrifuged liquid in another liquid.

15. In centrifugal purification or separating

- ing operations wherein a liquid subjected to the action of centrifugal force is discharged in a finely divided form, the process of preventing loss of the centrifuged substance which comprises outflowing from the locus of centrifugation any foreign gas carrying finely divided centrifuged substance, allowing settlement to separate a part of the centrifuged liquid from foreign gas carrying the remainder of the centrifuged substance, and maintaining a partial vacuum on the centrifuged substance while separating the gas from the centrifuged substance carried thereby.
- 15 16. In centrifugal purification or separating operations wherein a liquid subjected to the action of centrifugal force is discharged in a finely divided form, the process of preventing loss of the centrifuged substance which comprises outflowing from its locus of centrifugation any foreign gas carrying finely divided centrifuged substance, allowing settlement to separate a part of the centrifuged liquid from foreign gas carrying the remainder of the centrifuged substance,

and maintaining a partial vacuum on the centrifuged substance while separating the gas from the centrifuged substance carried thereby by contacting the gas with a liquid adapted to absorb the finely divided centrifuged liquid.

17. The combination with a centrifuge of the type wherein a substance subjected to the action of centrifugal force is discharged in a finely divided form, of a collecting vessel into which the centrifuged substance is adapted to be discharged, a receiving tank communicating with, and adapted to receive the centrifugal substance from, the collecting vessel, a conduit through which any gas carrying the centrifuged substance in vapor or liquid phase is adapted to escape from the tank, and means to separate from the gas any such escaping centrifuged substance that has not been absorbed in the centrifuged substance in the tank.

In testimony of which invention, I have hereunto set my hand, at Stockholm, Sweden, on this 8 day of July, 1926.

HANS OLOF LINDGREN
